[57] CLAIM

The ornamental design for a transducer pod, substantially as shown and described.

DESCRIPTION

FIG. 1 is a top and right side perspective view of a transducer pod showing my new design;

FIG. 2 is a right side elevational view, the left side being an identical image;

FIG. 3 is a front elevational view, the rear being an identical image;

FIG. 4 is a top plan view;

FIG. 5 is a bottom plan view;

FIG. 6 is a bottom and right side elevational view; and

FIG. 7 is a sectional view taken along line 7—7 of FIG. 4 thereof.

FIG.1.

FIG.2.

FIG. 3.

FIG. 4.

FIG. 5.

FIG. 6

FIG. 7
